UNITED STATES PATENT OFFICE.

WOLCOTT A. HULL, OF NEW YORK, N. Y., ASSIGNOR OF ONE-HALF TO THE ANSONIA BRASS AND COPPER COMPANY, OF SAME PLACE.

COUNTER-BALANCE FOR EXTENSION-CHANDELIERS.

SPECIFICATION forming part of Letters Patent No. 256,323, dated April 11, 1882.

Application filed January 26, 1882. (No model.)

To all whom it may concern:

Be it known that I, WOLCOTT A. HULL, of New York, in the county and State of New York, have invented certain new and useful 5 Improvements in Counter-Balances for Extension-Chandeliers, of which the following is a specification.

Weights for counterbalancing the extensible or movable part of an extension-chandelier have very commonly been made of cast metal and drilled to form a hole for fitting on its guide-rod. These weights are expensive to manufacture, and it is the object of my invention to simplify and cheapen the manufacture 15 of them.

To this end my invention consists in a counterbalancing-weight made of a number of pieces with cavities which, when put together, form a hole suitable for surrounding a guide-rod.

The invention further consists in the combination, with a counterbalancing-weight made in sections having cavities forming a hole for surrounding a guide-rod, of a shell inclosing 25 said sections, and having its upper and lower edges turned inward, so as to fit the guide-rod.

In the accompanying drawings, Figure 1 is a perspective view of a counterbalancing-weight embodying my invention and made in two parts. Fig. 2 is a sectional view of the same. Fig. 3 is a sectional view taken on a plane perpendicular to the plane of the sectional view, Fig. 2, and Fig. 4 is a perspective view of 35 one of the sections composing the weight.

Similar letters of reference designate corresponding parts in all figures.

A designates a counterbalancing-weight, made of two sections of cast-iron or other suitable metal, and each having a cavity, **a**. When these two sections are put together their two cavities form a round hole, which is adapted to surround a guide-rod. Preferably the opposite faces, **b**, of the sections are slightly concaved, so that they will fit snugly together at the edges.

B designates a shell of brass or other ornamental metal, which incloses the sections of the weight **A** and secures them together. 50 This shell is composed of two parts, which are connected together transversely to the meeting faces of the sections of the weight. They

are connected by folding or creasing their meeting edges together. The upper and lower edges of this shell are turned in, as at **d**, so 55 that they will fit a guide-rod snugly. The upper portion of the shell is also provided with a neck, **c**, which may be spun up and have its edges turned in over the upper turned-in edge of the shell. It will serve as a convenient 60 means by which the supporting-chains may be connected to the weight.

It will be seen that by my invention I produce a very simple and desirable counterbalancing-weight.

What I claim as my invention, and desire to secure by Letters Patent, is—

1. A counterbalancing-weight consisting of cast-metal sections provided with cavities which, when the sections are put together, 70 form a hole for surrounding a guide-rod, substantially as specified.

2. A counterbalancing-weight consisting of sections of cast metal provided with cavities which, when the sections are put together, 75 form a hole for fitting a guide-rod, and having their opposite faces concaved, substantially as specified.

3. The combination, with a counterbalancing-weight consisting of sections of cast metal provided with cavities which, when put together, form a hole for surrounding a guide-rod, of a shell inclosing said sections, substantially as specified.

4. The combination, with a counterbalancing-weight consisting of sections of cast metal provided with cavities which, when put together, form a hole for surrounding a guide-rod, of a shell inclosing the same and formed of two parts, which are connected transversely 90 to the meeting or opposite faces of the sections of the weight, substantially as specified.

5. The combination, with a counterbalancing-weight consisting of sections of cast metal provided with cavities which, when put together, form a hole for surrounding a guide-rod, of a shell inclosing the same and having its upper and lower edges turned inward to fit the guide-rod, substantially as specified.

WOLCOTT A. HULL.
